United States Patent Office.

ELBRIDGE S. KIMBALL, OF SPRINGFIELD, MASSACHUSETTS.

Letters Patent No. 98,069, dated December 21, 1869.

IMPROVED SPRING-BED BOTTOM.

The Schedule referred to in these Letters Patent and making part of the same.

To all whom it may concern:

Be it known that I, ELBRIDGE S. KIMBALL, of Springfield, in the county of Hampden, and State of Massachusetts, have made and invented a new and useful Improvement in Spring-Bed Bottoms; and I do hereby declare that the following is a full, clear, and exact description of the construction of the same, reference being had to the annexed drawings making a part of this specification, in which like letters mark like parts, and whereof—

Figure 1 is a side elevation;

Figure 2, a plan;

Figure 3, a transverse section of the end of the frame, coil-rod, and block; and

Figure 4, a detached side elevation of one-half of a double coil-spring.

My invention relates to that class of spring-bed bottoms in which narrow slats, provided with loops or leathers, are connected at each end with double-coil springs.

To enable others skilled in the art to practice my invention, I describe the same as follows:

In the accompanying drawing—

The part marked *a* represents the side of the frame; *b*, the end thereof, in which are set the legs of the double-coil spring *c c'*, the arms of which latter, *d d'*, are connected by a bar, *e e'*, from which projects a tongue, *f*, whereon is hooked the loop or leather *g*, connected with slat *h*, the whole spring being made of a single piece of elastic wire.

Passed through the coils of the several springs, and to steady the same, is a rod, *i*, supported and held in place by a block, *j*, and staple, *k*, which respectively rest on and enter into the frame-end *b*.

I form the double-coil lifter-spring *c c'* peculiarly, by providing the bar thereof, *e e'*, with a tongue, *f*, projecting therefrom rearward and downward, thus constituting such bar a rest or bearing for the loop *g*; and

My invention consists in the lifter-spring thus peculiarly formed, and in the combination of the same within the superincumbent loop *g*; the objects thereof being, by giving the loop *g* a rest or bearing on the bar *e e'*, to prevent the tearing out of such loop, to protect the mattress from the spring, and to prevent the rocking and swaying of the slat, without the use of a double or folded loop or leather.

Thus having described my improvement,

What I claim as new, and desire to secure by Letters Patent, is—

The double-coil lifter-spring *c c'*, formed as at *e e' f*, in combination with the superincumbent slat-loop *g*, all constructed and arranged in the manner and for the purpose specified.

E. S. KIMBALL.
